(57) **CLAIM**

I claim the ornamental designs for a bed step, as shown and described.

DESCRIPTION

FIG. 1 is a perspective view of the bed step of the invention.

FIG. 2 is a top plan view of the bed step of the invention.

FIG. 3 is a right side elevation view of the bed step of the invention.

FIG. 4 is a rear elevation view of the bed step of the invention.

FIG. 5 is a front elevation view of the bed step of the invention.

FIG. 6 is a left side elevation view of the bed step of the invention; and,

FIG. 7 is a bottom plan view of the bed step of the invention.

1 Claim, 3 Drawing Sheets
